UNITED STATES PATENT OFFICE.

JOHN W. COX, OF ERIE, PENNSYLVANIA, ASSIGNOR OF ONE-FOURTH TO GEORGE R. METCALF AND ONE-FOURTH TO EDWARD E. WALKER, BOTH OF ERIE, PENNSYLVANIA.

PACKING-MACHINE.

1,289,677.

Specification of Letters Patent. Patented Dec. 31, 1918.

Application filed February 15, 1917. Serial No. 148,832.

To all whom it may concern:

Be it known that I, JOHN W. COX, a subject of the King of Great Britain, having declared my intention of becoming a citizen 5 of the United States, residing at Erie, in the county of Erie and State of Pennsylvania, have invented new and useful Improvements in Packing-Machines, of which the following is a specification.

10 This invention relates to packing machines and consists in certain improvements in the construction thereof as will be herein-after fully described and pointed out in the claims.

15 More particularly the invention relates to a machine which is designed to load or pack receptacles where it is necessary to jar down the material. This is particularly true in loading the annealing pots of malleable castings wherein the castings are mixed with an annealing material, ordinarily such as oxid iron. Here it is necessary to shake down the annealing material so that it will fill the interstices between the castings. These annealing pots are ordinarily made in sections 20 so that it is desirable to have the top of each section flush with the floor so that it can be conveniently loaded with castings from the floor surface. Where several sections are used, this involves a means for adjusting the height of each section so that it will come flush with the floor.

25 The invention is illustrated in the accompanying drawings as follows:

30 Figure 1 shows a side elevation, partly in section, of the invention.

Fig. 2 a central section through the reversing valve.

35 Fig. 3 an enlarged section of the packing machine proper.

40 1 marks the receptacle. As shown this is formed in several sections which may be placed one above the other as they are loaded, thus making the loading of each 45 section more convenient. The sections are mounted on a platform or carrier 2 and this platform is adapted to be adjusted with relation to the floor 3 from which the receptacles are loaded.

45 50 The platform 2 is mounted on a plunger 4. The plunger extends into a cylinder 5.

An actuating fluid, such as water, is carried into the cylinder 5 by way of the pipe 6 carried by the plunger. The pipe 6 is connected through a hose 7 with a supply pipe 8. 55 The supply pipe is controlled by a three-way valve 8^a so that supply may be turned into the cylinder or the valve may be so thrown as to exhaust the water from the cylinder by way of the pipe 8^b. In this way the platform 2 may be nicely adjusted so as to bring the top of the section which is being loaded at or about flush with the floor 3 and the platform can be maintained in this position by simply closing the valve 8^a and locking 60 the fluid in the cylinder. Chains 9 are provided with the platform and the cylinder 5 to prevent the forcing of the plunger out of the cylinder.

65 The cylinder 5 has an extension 10 which 70 forms a plunger operating in a cylinder 11. The cylinder 11 is mounted on a base 12. Projections 13 extend from the cylinder 5 and bolts 14 extend from these projections through perforations 15 on the cylinder 11. 75 Nuts 17 are arranged on the bolts or studs 14 and these coming into contact with the projections 16 limit the upward movement of the plunger 10 and consequently the upward movement of the cylinder 5. It will 80 be noted that when this is moved upwardly through the action of the plunger 10, the plunger 4 maintains its relation to the cylinder 5.

85 The purpose of the plunger 10 operating as it does in the cylinder 11 is to form a shaker by means of which the material may be more thoroughly packed in the receptacles. To accomplish this, the plunger 10 is elevated and then the liquid under it is 90 freely released, allowing it to practically drop so as to supply sufficient shock to the material in the receptacle to assure its filling in the interstices in the castings.

95 The cylinder 11 is supplied through a pipe 18. This pipe 18 is connected with the main pipe 19. The pipe 19 has a T 20 from which branch pipes 21 and 22 extend to the valve chamber 23.

100 The valve which alternates the flow of liquid to and from the pipe 18 is as follows: The valve chamber 23 is provided with the

valve surfaces 24 and 25 to which lead the inlet port 26 and the exhaust port 27 respectively. The valves 28 and 29 control the ports 26 and 27. A valve stem 30 connects the valves 28 and 29 and forms a means of connection for actuating the valves. A supply pipe 31 leads to the valve chamber opposite the port 26. An exhaust pipe 32 leads from the port 27 and the pipe 21 leads from the valve chamber opposite the port 27. In general, the operation is to connect the pipe 31 and 22, to turn in the supply of liquid to raise the plunger 10, then close this connection and open the connection by way of the port 27 between the pipes 21 and 32 so as to exhaust the liquid and permit the plunger 10 to drop.

The valve is reciprocated through the stem 30 by the following mechanism: A bracket 33 is secured on one end of the stem. This bracket carries a pivoted latch 34 which is adapted to engage a bracket 35 extending from the piston rod 36 of a water motor 37. The water motor is supplied by a pipe 37^a and exhausts by a pipe 37^b and operates in the usual manner of water motors to give a reciprocating movement to the stem or piston 36. The latch 34 being connected with the bracket 35 is carried to the left as the piston 36 is carried to the left, and thus carries the valves to the left, closing the connection through the port 27 and opening the connection through the port 26. When the valve has approximately reached the limit of its travel, a cam projection 38 on the latch 34 contacts a shoulder 39 and trips the latch, thus freeing the valve from the stem 36. A spring 40 is secured to the opposite end of the stem 30 and to an anchor 41. Immediately the stem is released, this spring pulls the stem 30 and with it the valves toward the right, closing the connection through the port 26 and opening the connection through the port 27 so as to drop the plunger 10. During the next reciprocation of the motor 37 the latch 34 again engages the bracket 35 and this operation is repeated.

It is desirable to have the upward movement of the plunger 10 comparatively slow and the return movement rapid so as to give the receptacle sufficient shock. This is accomplished by placing the check valve 42 in the line 18 and providing a bypass 43 in which there is a regulating valve 44. The inflow of liquid through the pipe 18 must go through the pipe 43 and the rapidity of this flow may be controlled by adjusting the valve 44. On the other hand when the exhaust connection is made by way of the port 27 the return flow of liquid is free passing the check valve 42.

It will be seen, therefore, that by means of the elevator formed by the plunger 4, the

platform may be given any height desired to bring the top of each section in proper relation to the floor and the device may be properly shaken to settle the material in the receptacle through the action of the plunger 10.

I have shown two machines in the drawings. These are duplicates in structure but the second machine is supplied through a pipe 45 and the elevator is controlled through a pipe 46. The details of construction and the specific means of control are similar in both machines.

What I claim as new is:

1. In a packing machine, the combination of a platform adapted to support a receptacle; means for adjusting the height of the platform; and a shaker for the platform.

2. In a packing machine, the combination of a platform adapted to support a receptacle; means for adjusting the height of the platform; and a shaker operating through the means upon the platform.

3. In a packing machine, the combination of a platform adapted to support a receptacle; a plunger elevator for adjusting the height of the platform; and a shaker for the platform.

4. In a packing machine, the combination of a platform adapted to support a receptacle; a plunger elevator for adjusting the height of the platform; and a shaker operating through said elevator upon the platform.

5. In a packing machine, the combination of a carrier; means for adjusting the height of the carrier; a shaker for the carrier comprising a plunger; a cylinder in which the plunger is mounted; and means for alternately admitting and exhausting actuating fluid to and from the cylinder.

6. In a packing machine, the combination of a carrier; means for adjusting the height of the carrier; a shaker for the carrier comprising a plunger; a cylinder in which the plunger is mounted; and means for alternately admitting and exhausting actuating fluid to and from the cylinder, said means admitting the fluid at a slower rate than it exhausts the fluid.

7. In a packing machine, the combination of a carrier; means for adjusting the height of the carrier; a shaker for the carrier comprising a plunger; a cylinder in which the plunger is mounted; means for supplying actuating fluid to the cylinder; a valve controlling the flow of fluid to and from the cylinder; and devices for actuating the valve to alternate the flow of fluid to and from the cylinder.

8. In a packing machine, the combination of a carrier; a shaker for the carrier comprising a plunger; a cylinder in which the plunger operates; a fluid supply pipe lead-

ing to the cylinder; a check valve in the supply pipe preventing an inflow of liquid; and means for admitting a restricted flow of liquid through the supply pipe.

5. 9. In a packing machine, the combination of a carrier; a shaker for the carrier comprising a fluid actuated motor; means for

supplying actuating fluid to the motor; a valve controlling said means; and a motor actuating the valve.

10 In testimony whereof I have hereunto set my hand.

JOHN W. COX.
